DESIGN FOR A SHOE SOLE

Eugene Joseph McCarthy, Chelsea, Mass., assignor to A. G. Walton & Co., Inc., Chelsea, Mass., a corporation of Massachusetts

Application January 30, 1939, Serial No. 82,686

Term of patent 14 years

To all whom it may concern:

Be it known that I, Eugene J. McCarthy, a citizen of the United States, residing at Chelsea, in the county of Suffolk and Commonwealth of Massachusetts, have invented a new, original, and ornamental Design for a Shoe Sole, of which the following is a specification, reference being had to the accompanying drawing, forming part thereof.

In the drawing Fig. 1 is a plan view of a shoe sole showing my new design; and Fig. 2 is a section on the line 2—2 of Fig. 1.

I claim:

The ornamental design for a shoe sole, substantially as shown.

EUGENE JOSEPH McCARTHY.
